UNITED STATES PATENT OFFICE.

ALBERT E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

WORK SUPPORT FOR STOCK-FITTING MACHINES.

Original application filed April 14, 1919, Serial No. 289,880. Divided and this application filed December 11, 1920. Serial No. 430,019.

To all whom it may concern:

Be it known that I, ALBERT E. JOHNSON, a citizen of the United States, residing at Beverly, in the county of Essex and State 5 of Massachusetts, have invented certain new and useful Improvements in Work Supports for Stock-Fitting Machines; and I do hereby declare the following to be a full, clear, and exact description of the invention, such 10 as will enable others skilled in the art to which it appertains to make and use the same.

The present invention relates to work supports for stock fitting machines, and more 15 particularly to means for adjusting the work support of a stock fitting machine relatively to the operating instrumentalities of the machine in accordance with the thickness of the work to be operated upon.

20 The invention is herein shown as applied to the turn sole channeling machine disclosed in United States Letters Patent No. 1,506,182, granted Aug. 26, 1924, upon an application filed by the present inventor, from which the 25 present application is a division, but the invention is not limited in its use to the type of machine illustrated.

The object of the present invention is to 30 provide, in a shoe machine employing a work support, improved means for adjusting the work support relatively to the operating instrumentalities of the machine to provide for variations in the thickness of the work to be operated on, whereby an increased 35 range of adjustment may be obtained with the same amount of movement of the adjusting means as has heretofore been required.

To the accomplishment of this object and 40 such others as may hereinafter appear, as will readily be understood by those skilled in the art, the invention comprises the features and combinations of parts hereinafter described and particularly pointed out in the appended claims.

45 The preferred form of the invention is illustrated in the accompanying drawings, in which Figure 1 is a view, in rear elevation, of the sole channeling machine disclosed in said parent application, showing the application thereto of the improved means for adjusting the work support; Fig. 2 is a left end elevation of a portion of the machine shown in Fig. 1, illustrating particularly the work

support adjusting means; and Fig. 3 is a detail sectional view taken substantially on the line 3—3 of Fig. 2.

In the illustrated embodiment of the invention, the head 4 (Fig. 1) of the channeling machine, with its operating instrumentalities and the actuating mechanism therefor, is the same as is illustrated and described in said parent application. These parts are merely illustrative of a machine to which the present invention may be applied and, therefore, need not be described herein. 65 As shown, the work support comprises the usual circular table 6 having a slightly convex upper face for engaging the work. The table 6 is vertically movable to permit the insertion and removal of the work, as illustrated a turn sole, between the table and the operating instrumentalities of the machine. To this end the table 6 is supported upon a spindle 8 carried in a sleeve 10 which is 70 mounted for vertical movement in a bore 12 in the frame of the machine. The sleeve 10 is actuated to raise or lower the work support by means of mechanism which is indicated generally at 14 in Figs. 1 and 2, and which is connected through a chain 16 with a foot treadle, not shown, at the base of the machine. The mechanism 14 for raising and lowering the work support is substantially the same in its construction and mode 75 of operation as corresponding mechanism disclosed in Letters Patent of the United States No. 984,772, granted February 2, 1911, to William C. Meyer.

In Letters Patent of the United States to Adam H. Prenzel, Reissue No. 13,375, granted February 27, 1912, a turn channeling machine is disclosed having a work supporting table which is adjustable toward and from the knives of the machine, in accordance with variations in the thickness of the work, by a worm or screw that is threaded into a bore in the lower end of the spindle of said table. This worm, in said machine, is capable of being turned through a partial revolution to make the desired adjustment of the work table by means of a handle that is secured to the lower end of the worm. The complete range of adjustment for a variation of eight irons in sole thickness requires an angular movement of the handle through about one hundred eighty degrees. 100 105

In accordance with the present invention, the work supporting table is capable of being adjusted toward and from the operating instrumentalities of the machine to which it is applied, through the combined action of the threads of a double worm or screw, whereby the amount of movement of the table responsive to the amount of angular movement of the operating handle heretofore required is greatly increased. As shown in the drawings, the present means for vertically adjusting the table 6 for variations in sole thickness comprises a worm or screw in the form of a ring 18 which is internally and externally threaded in reverse directions and is screwed on the lower end of the sleeve 10 and into a bore 20 in the usual collar 22 which is fixed relatively to the ring 18 and forms a rigid part of the frame with respect to the work table. The sleeve 10 is prevented from rotating in the bore 12 by means of a guide pin 24 which is secured to the frame of the machine and enters an aperture in a horizontal lug 26 projecting from the upper end of the sleeve. The ring 18 is adapted to be turned within the collar 22 and thus vertically adjust the work table by means of a thumb piece 28 in the form of a pointer. This pointer cooperates with a scale 30 denoting irons, on the frame of the machine whereby the operator is enabled to determine the amount of vertical adjustment of the work table required for the thickness of the sole to be operated upon. The double thread construction of the adjusting worm or ring 18 augments the movement of the work table to such an extent that the entire eight iron range of adjustment required may be obtained by an angular movement of the thumb piece 28 through a relatively small angle, about ninety degrees, making the adjustment easy and speedy.

As shown, the work table 6, instead of having the usual step-by-step rotary movement, is mounted for free rotation upon a ball bearing 32 (Fig. 1) so that it may easily rotate to travel with the work feeding device of the machine during the effective movements of said device, thus providing for an even forward movement of the work. Such mounting of the work table, however, forms no part of the present invention.

The nature and scope of the present invention having been indicated and the preferred embodiment thereof having been specifically described, what is claimed as new, is:—

1. A work support for a stock fitting machine comprising, in combination, a bracket bored out to form a stationary sleeve, an internally-threaded supporting sleeve and a manually-operable toggle connecting it to the bracket, a work-supporting table, a plunger carrying the table and guided by the stationary sleeve, the plunger having a lower

externally-threaded portion concentrically arranged within the supporting sleeve, and an internally and externally threaded ring arranged between the supporting sleeve and the lower portion of the plunger in such a manner that turning the ring raises the plunger with respect to the ring and the ring with respect to the supporting sleeve to lift the table a substantial distance for a relatively small turning movement of the ring. 75

2. A work support for a stock fitting machine comprising, in combination, a stationary upper sleeve having a smooth inner surface, an internally threaded supporting sleeve arranged concentrically of and below the stationary sleeve, a work-supporting table, a plunger carrying the table and guided by the stationary sleeve, the plunger having a lower externally-threaded portion concentrically arranged within the supporting sleeve, and an internally and externally threaded ring between the supporting sleeve and the lower portion of the plunger in such a manner that turning the ring raises the plunger with respect to the ring and the ring with respect to the supporting sleeve to lift the table a substantial distance for a relatively small turning movement of the ring. 90

3. A support as defined by claim 2, in which the stationary sleeve is provided externally with a scale and the ring is provided with a thumb piece to be used to manipulate the ring, the thumb piece being shaped and arranged to provide a pointer to indicate on the scale the adjustment of the table. 100

4. A work support of the class described having, in combination, a stationary upper sleeve formed with a smooth inner surface, a table, a plunger supporting the table and guided by the stationary sleeve, the plunger being threaded at its lower end, a supporting member below the stationary sleeve which is reversely threaded with respect to the threaded part of the plunger, the threaded parts of the plunger and the supporting member being co-axially arranged, and an internally and externally threaded annular device connecting the supporting member and the plunger in such a manner that turning said device raises it with respect to the supporting member and simultaneously raises the plunger with respect to the annular device, to give a substantial vertical adjustment of the table for a relatively small movement of said device. 115

5. A work support of the class described having, in combination, a stationary upper sleeve formed with a smooth inner surface, a table, a plunger supporting the table and guided by the stationary sleeve, the plunger being threaded at its lower end, a supporting member below the stationary sleeve which is reversely threaded with respect to the threaded part of the plunger, the threaded parts of the plunger and the supporting member 125

being co-axially arranged, a toggle connecting said sleeve and said member, means for actuating the toggle to raise and lower the table, and an internally and externally threaded annular device connecting the supporting member and the plunger in such a manner that turning said device raises it with respect to the supporting member and simultaneously raises the plunger with respect to the annular device to give a substantial vertical adjustment of the table for a relatively small movement of said device. 10

ALBERT E. JOHNSON.
